CAN SALVAGERS

Roy W. Lewis, St. Clairsville, Ohio

Application September 3, 1958, Serial No. 759,838

14 Claims. (Cl. 153—2)

This application is a continuation-in-part of my application Serial No. 648,217, filed March 25, 1957, and now abandoned.

This invention relates to apparatus for salvaging cans and pertains more particularly to a device of this character, which is adapted to slit, longitudinally, the cylindrical side wall of a can (one end of which has previously been opened) and sever the bottom, or closed end, of the can from the can side wall, so as, ultimately, to convert the cylindrical side wall into a flat sheet and the bottom of the can, by severance from the side wall, into a flat disc. The flat sheet and the flat disc, will then be easier to store, pack and handle.

Discarded cans are rather bulky and occupy a great deal of space for the amount of metal contained in their construction. For this reason, it is highly desirable to provide some means for flattening them so that they may be compacted into substantially a dense mass. For this purpose, there are, of course, available large press type machines which can take a large number of cans or the like and compress them into a relatively small space substantially devoid of air spaces or voids so that the metal can be easily handled and shipped for re-claiming. However, it is not always practical to expend the amount of money necessary for obtaining press type machines since by their very nature they are rather massive and expensive construction and it is, therefore, highly desirable to provide a rather compact and portable means which is capable of re-claiming discarded cans and obtaining relatively flat sheets struck therefrom. It is, therefore, a primary object of this invention to provide a highly effective and yet compact inexpensive machine for re-claiming cans.

It is another object of this invention to provide a construction for salvaging or re-claiming cans wherein individual cans are placed on a mandrel and first slit lengthwise and then subjected to an end severing action, whereby the can is re-claimed in two parts, the can bottom and a substantially flat sheet which was originally the side wall of the can.

Still another object of this invention is to provide a device of the character described incorporating a relatively fixed frame and a can receiving mandrel fixed thereto, with there being swingably mounted on the frame a combined roller and knife assembly which is swung simultaneously into engagement with a can received on the mandrel so that the can is first slit lengthwise thereof and clamped by the roller against the mandrel such that rotation of the roller will rotate the can, the knife including a blade portion thereof adapted to sever the can bottom when the can is rotated by the roller, or there may be a rotary knife cooperating with the blade portion to sever the can bottom.

Another object of this invention is to provide a frame construction in accordance with the preceding object wherein the roller and knife are pivotally attached thereto about an axis inclined to the vertical and with the mandrel having a pair of longitudinally extending de-

2

pressions therein, one for receiving the cutting edge of the knife and the other for receiving a peripheral portion of the roller so as to achieve a firm gripping action of an associated can so that the roller, when rotated, will serve to rotate the can upon the mandrel and thus serve to sever the bottom of the can.

It will be appreciated that the can salvaging machine disclosed herein is readily adaptable in many circumstances. For example, the machine can be used in the home wherein the number of cans handled by the machine would be relatively small or the machine is useful in such establishments as gasoline service stations, restaurants, hotels and the like where the number of cans processed would be relatively large. The machine will find use under many and varied circumstances and will be extremely beneficial regardless of the volume of cans to be processed.

With the above and other objects in view, the invention consists in the construction and novel combination and arrangement of parts hereinafter fully described, illustrated in the accompanying drawings and pointed out in the claims hereto appended, it being understood that various changes in the form, proportions, and minor details of construction, within the scope of the claims, may be resorted to without departing from the spirit or sacrificing any of the advantages of the invention.

In the drawings:

Fig. 1 is a front elevational view of the salvaging machine constructed in accordance with this invention;

Fig. 2 is a side elevational view of the machine and showing the roller and knife assembly in partially withdrawn position;

Fig. 3 is a horizontal section taken substantially along the plane of section line 3—3 of Fig. 2 and showing the relationship of parts;

Fig. 4 is an enlarged transverse sectional view showing the position of parts with the roller and knife assembly withdrawn;

Fig. 5 is a view similar to Fig. 4 but showing the roller and knife in the engaged position and illustrating, in dotted lines, an associated can disposed upon the mandrel assembly;

Fig. 6 is a perspective view of the knife assembly;

Fig. 7 is an enlarged view of the handle end of Fig. 3 and showing the rotary knife; and

Fig. 8 is an elevation of the rotary knife and how it cooperates with the blade portion.

Referring now more particularly to Figs. 1, 2 and 3, the can salvaging machine will be seen to consist essentially of a frame assembly indicated generally by the reference character 10 having a base 11 in the form of a generally rectangular plate and upstanding therefrom a pair of substantially vertical plate-like side pieces 12 and 13 interconnected by a horizontal frame piece 14. As will be seen most clearly in Fig. 2, the side piece 13 rises from the rear edge of the base 11 and the intermediate or throat portion 15 of the side pieces is cut away, as shown, with the upper extremities of each side piece being enlarged to overhang. The other side piece 12 is of much greater width than the side piece 13, being devoid of the cut away throat portion 15 and instead is provided with an enlarged throat portion 16 and has fixed thereto a horizontally extending mandrel indicated generally by the reference character 17. The cut away throat portion 15 leaves the free end of the mandrel 17 open and accessible to the placement of an open can on the mandrel. The mandrel is of arcuate cross section as shown most clearly in Fig. 2 and is provided with a longitudinally extending V-shaped notch 18 and immediately rearwardly thereof with a semi-circular trough 19 coextensive in length with the notch 18, the purpose of which will be presently apparent.

The mandrel, as stated above, is attached at one end to the side piece 12 and extends therefrom horizontally toward the other side piece 13 but terminates in spaced relation thereto so that the mandrel is actually attached to the side piece 12 in cantilever fashion.

Also serving to interconnect the side pieces 12 and 13 is a horizontally extending deflector plate 20 having a concave rearward surface 21, see particularly Fig. 5, and terminating along its lower edge in a stepped portion 22, the purpose of which will also be presently apparent.

Preferably, although not necessarily, the entire frame structure may be integrally formed as, for example, by a single casting, although it is to be understood that the same may be built up of separate pieces with such separate elements being suitably secured together as by fasteners, welding or the like.

Fixed to the inner surface of the side piece 12 in horizontally inwardly projecting relation thereto are a pair of spaced ears 23 and 24, see particularly Fig. 5, and these ears are apertured to receive therethrough a pivot bolt member 25 suitably fixed to the ears and journaling therebetween a pivot block member 26. The angle of inclination of the pivot bolt 25 is in the neighborhood of 45° with respect to the vertical, as is illustrated in Fig. 5, so that the parts attached to the pivot block 26 may be swung upwardly and rearwardly when desired. A similar block member 27 is disposed at the opposite side of the machine, although this latter block is not in any way pivoted directly to the machine frame but is rather connected to the pivot block 26 by means of a knife blade assembly indicated generally by the reference character 28. Fig. 3 illustrates the manner in which the knife blade assembly rigidly interconnects the blocks 26 and 27, the knife being provided with laterally projecting ears 29 and 30 secured to the opposed inner faces of the block by means of suitable fasteners or the like. The blocks 26 and 27 are provided with journal holes receiving the opposite ends 31 and 32 of a roller axle and suitable means such as the cotter pins 33 and 34 may be utilized to longitudinally position the axle with respect to the blocks. Between the blocks, the axle carries a cylindrical roller element 35 having a friction producing surface thereon and the end 32 of the axle projects completely through the block 27 and through the side piece 13 and has fixed on its free end a crank assembly indicated generally by the reference character 36 so that the roller may be selectively hand turned. To receive the axle end 32, the side piece 13 is provided with an elongate slot 37 which is disposed at right angles to the axis of the pivot bolt 25, see particularly Fig. 2 so that when desired the entire roller and knife blade assembly may be swung about the pivot bolt 25 to an out-of-the-way position.

In use, a can suitable for salvaging and having one end thereof removed is slipped over the mandrel 17, the convexity of the upper surface of the mandrel conforming generally to the inner surface of the can. In order to permit the can to be placed on the mandrel, the roller and knife blade assembly must, of course, be swung away from the mandrel so as not to interfere with the can. The knife blade itself, as will be seen most clearly in Figs. 4 and 5, includes a main body portion 38 and a laterally projecting and longitudinally extending knife edge portion 39 which is disposed generally at right angles to the axis of the pivot bolt 25. The can is indicated in dotted lines by the reference character 40 in Fig. 5 and it will be evident that when the roller and knife blade assembly is swung toward the mandrel 17, the knife blade portion 39 will sever the can along a longitudinal line and in the final position of the roller and knife blade as shown in Fig. 5 and as opposed to an intermediate position illustrated in Fig. 4, the roller 35 will be forced into the trough 19 to deform the can so that when the roller is subsequently turned, the deformed

edge portion 46 thereof will be directed generally in an upward direction and against the rearward face 21 of the deflector plate 20. The previously mentioned stepped portion 22 formed along the lower edge of the deflector plate receives the upper edge of the main body portion 38 of the knife blade assembly and it is preferred that the rear face 47 of the knife blade assembly lies substantially flush with the concave face 21 of the deflector plate. Insofar as the notch 22 is concerned, it is preferred that the same serve to finally position the knife blade so as to prevent the cutting edge of the blade portion 39 from actually contacting the bottom of the V-shaped notch 18 which might otherwise tend to dull the knife edge and seriously affect its longevity.

Fig. 6 most clearly illustrates the knife blade construction and, in addition to the previously mentioned main body portion 38 and blade portion 39, the knife blade is provided with an auxiliary blade element 49 having a knife edge 50 disposed at right angles to the main knife edge. The purpose of the auxiliary knife blade 49 is to sever the bottom end of an associated can adjacent the free end of the mandrel 17. The auxiliary knife blade 49, of course, penetrates the can in a direction perpendicularly to the line of severance effected by the blade element 39 when the parts are initially disposed in the final position as shown in Fig. 5 and when the roller 35 is rotated to feed the can around the mandrel, the auxiliary knife continues its severing action circumferentially of the can. In this way, an opened can having the top removed is finally separated into two pieces, one a relatively flat rectangular strip or sheet constituting the original side wall of the can and the other a circular disc portion which was originally the bottom of the can. This permits the salvaged cans to be very easily packed and confined within a relatively small space.

The supporting surface of the mandrel upon which the inner surface of the can rests is convex and the cylindrical roller operating in the arcuate trough in the mandrel serves to deform the can side wall in a direction opposite to that in which it is normally bent so that the combined action of the roller taken in conjunction with the mandrel trough and feeding the circular side wall of the can between the same effects a straightening action upon the can side wall tending to cause it to assume a substantially flat sheet-like form.

The proximity of the knife blade and the roller serves to produce the beneficial effect of directing the severed longitudinal edge of the can which is disposed nearest the roller upwardly toward the rear surface of the deflector plate particularly in view of the fact that the roller forces the longitudinal area of the can immediately behind the severed edge down into the trough in the mandrel. Thus the natural effect is to constrain the severed free edge of the can to assume an upwardly projecting position as is clearly shown in the drawings in Fig. 5.

It will be appreciated that the mandrel as specifically shown in the drawings and described as above may be reversed in position with respect to the frame. That is, the mandrel can be attached to the frame at the side thereof opposite that side upon which the cutter blade and roller assembly are pivoted. Certain advantages accrue from this arrangement, for example, this permits a can to be fed onto the mandrel with one hand while the other hand operates the cutter blade and roller assemblies to swing the same into operative position and rotate the crank, thus increasing the speed of operation. Also, because of the change in leverage by placing the knife edge 49 near the hinge pin, the downward pressure on the knife and roller assembly required to penetrate the can by the knife 49 would be less.

As is shown most clearly in Figs. 1 and 2, a handle member H is fixed to the block 27 so that the operator may hold the roller 35 firmly into engagement with the

5 edge portion 46 thereof will be directed generally in an upward direction and against the rearward face 21 of the deflector plate 20. The previously mentioned stepped portion 22 formed along the lower edge of the deflector plate receives the upper edge of the main body portion 38 of the knife blade assembly and it is preferred that the rear face 47 of the knife blade assembly lies substantially flush with the concave face 21 of the deflector plate. Insofar as the notch 22 is concerned, it is preferred that the same serve to finally position the knife blade so as to prevent the cutting edge of the blade portion 39 from actually contacting the bottom of the V-shaped notch 18 which might otherwise tend to dull the knife edge and seriously affect its longevity.

Fig. 6 most clearly illustrates the knife blade construction and, in addition to the previously mentioned main body portion 38 and blade portion 39, the knife blade is provided with an auxiliary blade element 49 having a knife edge 50 disposed at right angles to the main knife edge. The purpose of the auxiliary knife blade 49 is to sever the bottom end of an associated can adjacent the free end of the mandrel 17. The auxiliary knife blade 49, of course, penetrates the can in a direction perpendicularly to the line of severance effected by the blade element 39 when the parts are initially disposed in the final position as shown in Fig. 5 and when the roller 35 is rotated to feed the can around the mandrel, the auxiliary knife continues its severing action circumferentially of the can. In this way, an opened can having the top removed is finally separated into two pieces, one a relatively flat rectangular strip or sheet constituting the original side wall of the can and the other a circular disc portion which was originally the bottom of the can. This permits the salvaged cans to be very easily packed and confined within a relatively small space.

The supporting surface of the mandrel upon which the inner surface of the can rests is convex and the cylindrical roller operating in the arcuate trough in the mandrel serves to deform the can side wall in a direction opposite to that in which it is normally bent so that the combined action of the roller taken in conjunction with the mandrel trough and feeding the circular side wall of the can between the same effects a straightening action upon the can side wall tending to cause it to assume a substantially flat sheet-like form.

The proximity of the knife blade and the roller serves to produce the beneficial effect of directing the severed longitudinal edge of the can which is disposed nearest the roller upwardly toward the rear surface of the deflector plate particularly in view of the fact that the roller forces the longitudinal area of the can immediately behind the severed edge down into the trough in the mandrel. Thus the natural effect is to constrain the severed free edge of the can to assume an upwardly projecting position as is clearly shown in the drawings in Fig. 5.

It will be appreciated that the mandrel as specifically shown in the drawings and described as above may be reversed in position with respect to the frame. That is, the mandrel can be attached to the frame at the side thereof opposite that side upon which the cutter blade and roller assembly are pivoted. Certain advantages accrue from this arrangement, for example, this permits a can to be fed onto the mandrel with one hand while the other hand operates the cutter blade and roller assemblies to swing the same into operative position and rotate the crank, thus increasing the speed of operation. Also, because of the change in leverage by placing the knife edge 49 near the hinge pin, the downward pressure on the knife and roller assembly required to penetrate the can by the knife 49 would be less.

As is shown most clearly in Figs. 1 and 2, a handle member H is fixed to the block 27 so that the operator may hold the roller 35 firmly into engagement with the

5 edge portion 46 thereof will be directed generally in an upward direction and against the rearward face 21 of the deflector plate 20. The previously mentioned stepped portion 22 formed along the lower edge of the deflector plate receives the upper edge of the main body portion 38 of the knife blade assembly and it is preferred that the rear face 47 of the knife blade assembly lies substantially flush with the concave face 21 of the deflector plate. Insofar as the notch 22 is concerned, it is preferred that the same serve to finally position the knife blade so as to prevent the cutting edge of the blade portion 39 from actually contacting the bottom of the V-shaped notch 18 which might otherwise tend to dull the knife edge and seriously affect its longevity.

Fig. 6 most clearly illustrates the knife blade construction and, in addition to the previously mentioned main body portion 38 and blade portion 39, the knife blade is provided with an auxiliary blade element 49 having a knife edge 50 disposed at right angles to the main knife edge. The purpose of the auxiliary knife blade 49 is to sever the bottom end of an associated can adjacent the free end of the mandrel 17. The auxiliary knife blade 49, of course, penetrates the can in a direction perpendicularly to the line of severance effected by the blade element 39 when the parts are initially disposed in the final position as shown in Fig. 5 and when the roller 35 is rotated to feed the can around the mandrel, the auxiliary knife continues its severing action circumferentially of the can. In this way, an opened can having the top removed is finally separated into two pieces, one a relatively flat rectangular strip or sheet constituting the original side wall of the can and the other a circular disc portion which was originally the bottom of the can. This permits the salvaged cans to be very easily packed and confined within a relatively small space.

The supporting surface of the mandrel upon which the inner surface of the can rests is convex and the cylindrical roller operating in the arcuate trough in the mandrel serves to deform the can side wall in a direction opposite to that in which it is normally bent so that the combined action of the roller taken in conjunction with the mandrel trough and feeding the circular side wall of the can between the same effects a straightening action upon the can side wall tending to cause it to assume a substantially flat sheet-like form.

The proximity of the knife blade and the roller serves to produce the beneficial effect of directing the severed longitudinal edge of the can which is disposed nearest the roller upwardly toward the rear surface of the deflector plate particularly in view of the fact that the roller forces the longitudinal area of the can immediately behind the severed edge down into the trough in the mandrel. Thus the natural effect is to constrain the severed free edge of the can to assume an upwardly projecting position as is clearly shown in the drawings in Fig. 5.

It will be appreciated that the mandrel as specifically shown in the drawings and described as above may be reversed in position with respect to the frame. That is, the mandrel can be attached to the frame at the side thereof opposite that side upon which the cutter blade and roller assembly are pivoted. Certain advantages accrue from this arrangement, for example, this permits a can to be fed onto the mandrel with one hand while the other hand operates the cutter blade and roller assemblies to swing the same into operative position and rotate the crank, thus increasing the speed of operation. Also, because of the change in leverage by placing the knife edge 49 near the hinge pin, the downward pressure on the knife and roller assembly required to penetrate the can by the knife 49 would be less.

As is shown most clearly in Figs. 1 and 2, a handle member H is fixed to the block 27 so that the operator may hold the roller 35 firmly into engagement with the

can as the handle 36 is turned. This handle member is, therefore, useful in preventing the roller from disengaging the can as the handle 36 is turned, which might otherwise occur.

There may be also provided a rotary disc knife blade 51 having a cutting edge 52 mounted on the axle 32 which will engage the can adjacent the closed end thereof when the knife and roller assembly is moved downwardly onto the can and will make an initial cut in the can at substantially right angles to the cut made by the knife edge 39. Upon rotation of the can body by the roller 35, the cutting edge 52 of the rotary disc knife will continue the cut around the periphery of the can so as to sever the closed end from the body thereof.

The rotary disc knife 51 may be used by itself in conjunction with the longitudinal knife 39 to sever the can end or it may be used in conjunction with the auxiliary blade 49 carried by the knife assembly 28.

When used in conjunction with the auxiliary blade 49, the blade 49 will make the first cut in the can body to the point *a* in Fig. 8 where the cutting edges of each knife cross each other thus giving a shearing action between the two blades when the can is rotated by the roller 35. However, point *a* must never be left of axis line B—B otherwise the disc knife 51 would strike the can wall before auxiliary knife 49 had penetrated to the axis. It is therefore better to make the auxiliary knife 49 a little deeper, as shown by the dotted line 49' which would move the shearing point to the right as at *b*. When so extended, the auxiliary knife 49 would have completed its cut of the can wall to the point *b* before the disc knife 51 could come into contact with the metal to be cut. When the roller 35 is rotated by the crank handle 36 the body of the can is fed through the shearing points *a* or *b*.

I claim:

1. A machine for salvaging cans comprising a frame including a base and a pair of spaced uprights fixed to the base, a mandrel rigidly secured at one end to one of said uprights and extending horizontally therefrom toward the opposite upright and terminating in a free opposite end adapted to have an open end of a can slid thereon, a knife and roller assembly pivotally fixed to said frame for movement toward and away from said mandrel between a remote position and an operative position substantially parallel to and adjacent said mandrel to engage and longitudinally sever the side wall of a can disposed on said mandrel, cutting means adjacent to and substantially at right angles to the free end of the mandrel to sever the uncut end of the can, the roller then engaging and rotating the can body, and means for rotating said roller.

2. A machine for cutting and straightening a tubular body comprising a frame having a horizontally disposed mandrel fixed thereto in cantilever fashion so as to receive the tubular body thereon, knife means carried by said frame for movement toward the mandrel for longitudinally severing the cylinder wall of the tubular body disposed thereon, said mandrel having bending means on the surface thereof, and a rotatable roller carried by said frame for movement toward said bending means and into engagement with the cylinder wall of the severed body disposed on the mandrel to rotate and reversely bend the severed body wall whereby rotation of the roller in cooperation with the bending means straightens the severed body wall and the sheet form.

3. A can salvaging machine comprising a frame having a horizontally disposed mandrel thereon for receiving a can body having at least one end removed, knife means for longitudinally severing the cylinder wall of a can on the mandrel, cutting means adjacent to and substantially at right angles to one end of the mandrel to sever the uncut end of the can, said mandrel having a convex outer surface, and a roller hingedly carried by said frame for movement into longitudinal engagement with a longi-

tudinally severed can on said mandrel whereby rotation of the roller will feed the can cylinder wall from the roller thus converting it to a generally flat, sheet-like form.

4. A can salvaging machine comprising a frame having a horizontally disposed mandrel thereon for receiving a can body having at least one end removed, knife means for longitudinally severing a can on the mandrel, cutting means adjacent to and substantially at right angles to one end of the mandrel to sever the uncut end of the can, said mandrel having a convex outer surface and provided with a longitudinally extending, concave roller-receiving trough, and a roller hingedly carried by said frame for movement into longitudinal engagement with a longitudinally severed can on said mandrel and forcing the can into the trough whereby rotation of the roller will feed the can cylinder wall from the roller thus converting it to a generally flat, sheet-like form.

5. A can salvaging machine comprising a frame having a horizontally disposed mandrel rigid therewith and adapted to support a can having at least one end removed thereon, said mandrel having a convex supporting surface to conform with the inner surface of a can, a knife and roller assembly pivoted to said frame for swinging movement toward and away from said mandrel such that the can is longitudinally severed by the knife while the roller engages the can wall, cutting means adjacent to and substantially at right angles to one end of the mandrel to sever the uncut end of the can, and means for rotating said roller to feed the can wall between the roller and mandrel to straighten the same into substantially flat, sheet-like form.

6. A can salvaging machine comprising a frame including a rigid, horizontally disposed mandrel having a convex upper surface for supporting a can having at least one end removed, said mandrel having a longitudinally extending, arcuate trough in its upper surface, a roller pivotally carried by said frame for movement toward and away from said mandrel and being received, in one position, within said trough, means for rotating said roller to feed said can wall between the mandrel and roller, cutting means adjacent to and substantially at right angles to one end of the mandrel to sever the uncut end of the can, and knife means for longitudinally cutting the side wall of a can supported on the mandrel.

7. A can salvaging machine comprising a frame having a pair of spaced, upstanding side pieces, a horizontally disposed mandrel fixed to one side piece and extending toward but terminating short of the other side piece, said mandrel having a convex upper surface for supporting a can having at least one end removed thereover, a pivot block hingedly secured to said one side piece about an axis inclined to the vertical and spaced rearwardly from said mandrel, a journal block disposed adjacent said other side piece, a knife blade assembly fixedly interconnecting said journal block and said pivot block and disposed on the sides thereof facing said mandrel, cutting means adjacent to and substantially at right angles to one end of the mandrel to serve the uncut end of the can, a roller journaled between said blocks and including means for selectively rotating the same, said knife blade assembly and said roller being disposed, in one position of the same, closely adjacent said mandrel so as to longitudinally slit the side wall of a can supported thereon and engage the roller against the can.

8. In a can salvaging machine as defined in claim 7 wherein said side pieces are interconnected by an arcuate deflector plate disposed forwardly and above said mandrel, said knife blade being engageable with the lower edge of said deflector plate in said one position of the knife.

9. In a can salvaging machine as defined in claim 7 wherein said mandrel is provided with a longitudinally extending groove in its upper surface and in rearwardly spaced parallel relation thereto with an arcuate trough, said groove receiving said knife blade and said trough re-

ceiving a peripheral portion of said roller in said one position of the same.

10. In a can salvaging machine as defined in claim 7 wherein said side pieces are interconnected by an arcuate deflector plate disposed forwardly and above said mandrel, said knife blade being engageable with the lower edge of said deflector plate in said one position of the knife, said mandrel being provided with a longitudinally extending groove in its upper surface and in rearwardly spaced parallel relation thereto with an arcuate trough, said groove receiving said knife blade and said trough receiving a peripheral portion of said roller in said one position of the same.

11. A can salvaging machine comprising a frame having a horizontally disposed mandrel rigid therewith and adapted to support thereon a can having at least one end removed therefrom, said mandrel having a convex supporting surface to conform with the inner surface of a can, a knife and roller assembly pivoted at one end thereof to said frame for swinging movement toward and away from said mandrel such that the can wall is longitudinally severed by the knife while the roller engages the can wall, cutting means positioned adjacent the free end of the knife and roller assembly and at substantially right angles to the knife for cutting and removing the uncut end of the can, and means for rotating said roller to feed the can wall between the roller, mandrel and cutting means to remove the uncut end therefrom and to straighten the can cylinder wall into substantially flat sheet-like form.

12. A can salvaging machine as defined in claim 11, wherein the cutting means is a rigid blade adjacent the free end of the knife and positioned at right angles with respect to the knife and integral therewith so that as the knife and roller assembly is pivoted to move toward and mandrel and the can resting thereon the cutting

means will, together with the pivoted end of the knife, make right angle cuts in the body of the can and when the body has been completely slit longitudinally thereof the cutting means will also, upon rotation of the roller, cut and remove the other end from the can body.

13. A can salvaging machine as defined in claim 11 wherein the cutting means is a rotary disc knife mounted on the roller axle adjacent the free end of the knife and roller assembly and positioned at right angle with respect to the longitudinal knife so that as the knife and roller assembly is pivoted toward the mandrel and the can resting thereon, the cutting means will together with the knife, make right angle cuts in the body of the can and when the body has been slit longitudinally the cutting means will, upon rotation of the roller, cut and remove the other end from the can body.

14. A can salvaging machine as defined in claim 11 wherein the cutting means comprises a rotary disc knife mounted on the roller axle and a rigid knife adjacent the free end of the knife and integral therewith each knife being positioned at right angles with respect to the knife and roller assembly, so that as the knife and roller assembly is pivoted toward the mandrel and the can resting thereon, the cutting means will together with the longitudinal knife make right angle cuts in the body of the can with the rotary disc knife and the rigid knife cooperating with each other to act as shears and when the can body has been severed longitudinally the cutting means acting as shears will, upon rotation of the roller, cut and remove the other end from the can body.
